UNITED STATES PATENT OFFICE.

HOMER B. MOORE, OF FORT SCOTT, KANSAS.

DESIGN FOR A RIBBON-SPOOL RACK.

SPECIFICATION forming part of Design No. 31,291, dated July 25, 1899.

Application filed June 26, 1899. Serial No. 721,967. Term of patent 7 years.

To all whom it may concern:

Be it known that I, HOMER B. MOORE, of the city of Fort Scott, Bourbon county, State of Kansas, have invented and produced a new and original Design for a Ribbon-Spool Rack, of which the following is a full, clear, and exact description, reference being had to the accompanying drawings, forming a part hereof.

- o Figure 1 is a front elevation of a ribbon-spool rack, showing my new design. Fig. 2 is an end elevation thereof.

As shown in the drawings, the leading or material feature of my design consists of the rectangular frame 1, the top corners of which terminate in ornamental projections 2, and midway between the vertical side portions of the frame is the vertical body 3, and midway between this body and the side portions of the frame are the vertically-arranged stand-

ards 4, from which project at regular intervals the horizontally-arranged branches 5. These branches all lie parallel with each other and occupy the same vertical planes as do the top and bottom portions of the frame 1. 25 At the lower outer corners of the rectangular frame 1 are arranged the ornamental base portion 6, which base portions are arranged so that the frame 1 is held a slight distance above the plane on which the base portions 30 rest.

I claim—

The design for a ribbon-spool rack, substantially as herein shown and described.

In testimony whereof I affix my signature 35 in presence of two witnesses.

HOMER B. MOORE.

Witnesses:

EDWARD E. LONGAN,
M. P. SMITH.
